Primary Examiner — Lauren D McVey*Assistant Examiner* — Elisa M Pujals(57) **CLAIM**

The ornamental design for a doll, as shown and described.

DESCRIPTION

FIG. 1 is a front perspective view of a doll, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1; and, FIG. 11 is an enlarged detail view of area 11 in FIG. 1.

The evenly spaced broken lines in the drawings illustrate portions of the doll, which form no part of the claimed design.

The dot-dash broken lines indicating an enlargement portion of the design form no part of the claimed design.

1 Claim, 11 Drawing Sheets(56)
